LOCKING DEVICE FOR TRACK SWITCHES
OR THE LIKEHarry R. Smith, Wilkinsburg, Pa., assignor to
Westinghouse Air Brake Company, a corpora-
tion of Pennsylvania

Application April 16, 1948, Serial No. 21,443

8 Claims. (Cl. 246—159)

1

My invention relates to locking devices, and particularly to electric locks for preventing the unauthorized operation of outlying railway traffic controlling devices, such as track switches, derails, or the like.

In railway signaling and traffic controlling systems, such outlying track switches are moved by a hand-throw lever and electric locking devices are used to retain the lever in one of its extreme positions. These locking devices commonly include both padlocks and additional locks electrically controlled from a distant point. This additional electrical control prevents authorized persons provided with keys for opening the padlocks from releasing the locking mechanism to operate the switch unless conditions are proper for such operation. The distant electric control is imposed on the electric lock by means of an external control circuit which may be governed either by a manual control established by an operator of a remote control system, such as a centralized traffic control system, or by an automatic control established by track circuits, positions of signals, etc., or by both manual and automatic controls. An electric lock of this type is shown in Letters Patent of the United States No. 2,387,115, granted October 16, 1945, to Herbert L. Bone, for Electric Lock.

Electric locks of the prior art, such as the one shown in the Bone patent previously referred to, have usually been provided with two pedals, one for releasing pressure on the padlock so that it could be removed, and another for releasing the switch lock itself. Such locks have also been provided with emergency release mechanisms by which an operator at the switch could release the lock without waiting for the electrical control circuit to be energized.

It is an object of my invention to provide an improved and simplified locking device of the type described.

Another object is to provide such a locking device for a railway track switch in which a single pedal is operated initially to permit removal of a padlock and then is moved additionally in the same direction to release the lock completely.

Another object is to provide an improved emergency release mechanism for a lock of the type described. A further object is to provide the emergency release with contacts which close a circuit to indicate at a remote point that the emergency release has been used.

Another object is to provide a lock of the type described with an improved indicator for informing a switchman that the device is elec-

2

trically locked, so that he will not make futile attempts to release the lock when the electric lock is imposed.

I accomplish these objects by providing a locking device including a latch of conventional construction movable between locking and unlocking positions. The latch is biased by a spring to its extreme locking position. A single foot pedal is provided for moving the latch in opposition to the spring. Initial movement of the latch by the foot pedal releases a padlock so that the latter may be removed. Then the lock is released completely by a continuing movement of the pedal in the same direction. An electric lock operated by an electromagnet is provided to prevent movement of the pedal and latch to its released position unless a control circuit for the electromagnet is energized.

My emergency release mechanism is operated by a push button accessible through a hand hole closed by a cover which is padlocked. The push button mechanically releases the normally electrically operated locking mechanism and also closes a pair of electrical contacts which complete a circuit to indicate at a remote point that the emergency release has been used.

A signal lamp within the casing is electrically connected with the lock releasing electromagnet so as to be energized whenever the electromagnet is energized. The switchman is thereby advised whether manual release of the lock can be accomplished by means of the pedal.

Other objects and characteristic features of my invention will become apparent as the description proceeds.

I shall describe one form of electric lock embodying my invention, and shall then point out the novel features thereof in claims.

In the accompanying drawings, Fig. 1 is an elevational view of a switch operating mechanism provided with an electric lock embodying my invention. Fig. 2 is a plan view of the electric lock shown in Fig. 1, the cover of which has been removed to illustrate the parts. Fig. 3 is a sectional view of the electric lock shown in Fig. 1 taken substantially on the line III—III of Fig. 2. Fig. 4 is a sectional view of the electric lock shown in Fig. 1 taken substantially on the line IV—IV of Fig. 2. Fig. 5 is a sectional view on a larger scale taken substantially on the line V—V of Fig. 4. Fig. 6 is a view on an enlarged scale, partly in section on the line VI—VI of Fig. 7 and partly in elevation, of a portion of the electric lock shown in Fig. 4. Fig. 7 is a sectional view of the portion of the electric lock

shown in Fig. 6 taken on the line VII—VII of Fig. 6. Fig. 8 is a fragmentary sectional view taken on the line VIII—VIII of Fig. 6.

Similar reference characters refer to similar parts in each of the several views.

Referring first to Fig. 1, an electric lock A embodying my invention and a switch operating mechanism B are so arranged on the ties 1 of a railway track switch that the hand-throw lever 2 of the mechanism B rests in a jaw 3 of the lock when the lever 2 occupies its normal position as shown. The switch operating mechanism B may be of any desired construction so connected to the movable switch points that the lever 2 controls the movement of the points, but as here shown the mechanism B is of the type shown, and described in Letters Patent of the United States No. 2,184,870, granted to Herbert L. Bone and Kenneth J. J. McGowan on December 26, 1939, for Railway Switch Operating Mechanisms.

Referring now to the remaining drawings, the electric lock A is provided with an upper casing 4 and a lower casing 5. Casings 4 and 5 are bolted together by means of elongated through bolts 6. Casing 4 is closed at its upper end by a removable cover 7. The cover 7 is apertured to loosely receive a wing-headed stud 7a by means of which the cover may be fastened down. This stud 7a is receivable in a tapped hole in a bracket 8, which is mounted on upper casing end walls 4a and 4b by tap bolts 9. The cover 7 is also provided with a staple 7b in which a padlock may be inserted so as to interfere with rotation of the stud 7a and thereby lock the cover in place. The lower casing 5 is provided with an extension 5a of which the jaw 3 is an integral part. The extension 5a is provided on its front side with two spaced vertical standards 10 which support a pivot pin 11. Pivotedly mounted on the pin 11 between the standards is a lever latch 12 movable between an extreme latching position and an extreme unlatching position. Lever latch 12 is provided with a nose portion 12a which, when the latch occupies a latching position (as shown in Fig. 3), projects into the upper end of the jaw 3 in such manner that it prevents movement of the lever 2 into or out of the jaw. When the latch 12 is moved to an unlatching position, nose portion 12a is withdrawn from the jaw. The latch 12 is also provided with a hole 12b so disposed that the bail 13 of a padlock (see Fig. 3) can be inserted through the hole 12b when the latch occupies the latching position. Notches 10a formed in the standards 10 are in alignment with hole 12b when the latch 12 is in its latching position.

Pivotedly mounted between the standards 10 below the latch 12 on another pin 14 is a foot pedal 15 provided with a finger 15a which projects into and cooperates with a recess 12c in the lower edge of the latch 12 in such manner that counterclockwise movement of the foot pedal will cause clockwise movement of the latch. The foot pedal 15 is also provided with a depending portion 15b having slotted bifurcations which straddle the outer end of a rod 16. The rod 16 extends through the casing extension 5a below the jaw 3 and projects at its inner end into the lower casing 5. The foot pedal 15 is operatively connected with the rod 16 by a pin 17 extending through the slots in the bifurcated portion 15b and a clearance hole in the rod.

The rod 16 is slidably supported adjacent its inner end 16b in a grooved pedestal 18 formed

integrally with the bottom side of the lower casing 5. The rod 16 is also slidably supported adjacent its outer end by a sleeve 19 suitably secured in an opening provided for the rod in the casing extension 5a. A spring retaining nut 20 is secured to the rod and a tension spring 21 is disposed on the rod between the sleeve 19 and the nut 20. One end of the spring 21 is suitably attached to the sleeve 19, such as by means of threads provided on the periphery of the sleeve 19, and the other end of the spring 21 is similarly attached to the nut 20. Sleeve 19 and nut 20 are so adjusted that the spring 21 is under tension sufficient to bias the foot pedal 15 in a clockwise direction, as viewed in Fig. 3, to an extreme raised position in which a stop surface 15c on the rear edge of the foot pedal engages a confronting stop surface 3a on the outer face of the jaw 3. The extreme right-hand position to which the rod can be moved is limited by engagement of a shoulder 16a with the outer end of the sleeve 19.

When the foot pedal 15 is in its extreme raised position as described above, the lever latch 12 is rotated counterclockwise from the position shown in Fig. 3, to its extreme latching position in which the nose portion 12a is fully projected into jaw 3. In this extreme position of the latch 12 the hole 12b in the latch will have rotated past the notches 10a in the standards 10 to a position below the notches in which padlock bail 13 cannot be inserted in the hole. In order to padlock the lever latch 12, it is then necessary to depress the foot pedal 15 a slight amount. When the foot pedal is moved to an extreme depressed position in which the shoulder 16a engages the sleeve 19, the latch 12 is rotated clockwise, as viewed in Fig. 3, to its extreme unlatching position in which nose portion 12a is out of the path of movement of the lever 2.

In the unlatching position just described, foot pedal finger 15a will have been rotated to a position in which it is clear of an opening 22 (see Fig. 3) in one of the standards 10. As best seen in Fig. 1, the free end 23a of a lock rod 23 is loosely supported to slide in the opening 22. The other end 23b of rod 23 is eccentrically pivoted to the hub of the hand-throw lever 2 so that when lever 2 is swung upwardly out of jaw 3, the rod will be moved to the right, as viewed in Fig. 1, or forwardly as viewed in Fig. 3, blocking the finger 15a. This action serves to retain the foot pedal 15 in its depressed position and the latch 12 in its unlatched position in opposition to the bias of the spring 21. The lever latch 12 and foot pedal 15 are therefore held in their respective unlatched and depressed positions during movement of lever 2 and during the time the lever 2 occupies its reverse position. The return of the hand-throw lever to its normal position in jaw 3 will cause movement of the rod 23 to the left, as viewed in Fig. 1, to the position in which the free end of the rod will have moved out from behind finger 15a, allowing the foot pedal 15 and the coacting lever latch 12 to rotate once more under the bias of spring 21 to their respective extreme raised and latching positions.

The portion of the locking device thus far described relates to means for applying padlock control to a spring-loaded lever latch. The locking device also comprises electrical means for at times locking the hand-throw lever in its normal position.

This electrical means includes an electro-magnet the energization of which is controlled

from a distant point over a control circuit. The control circuit forms no part of my present invention, and it is sufficient for present purposes to point out that this circuit controls the energization of the electromagnet in accordance with the desires of a remote operator or the condition of one or more signal circuits.

Referring again to the drawings, a gear 24 provided with toothed sectors in its upper and lower edges is pivotally mounted on a pin 25 so that its lower gear teeth mesh with a rack 16b provided on the upper surface of the inner end of rod 16. Pin 25 is supported in a bearing frame 26 secured to bosses in the lower casing 5 by tap bolts 27 (see Fig. 3). Rotatably mounted above gear member 24 is a shaft 28. Shaft 28 is supported at one end in a bearing mounted in the end wall 4a of upper casing 4 and at its other end in a bearing 29a formed in a bracket 29 secured to a boss in the casing 4 by tap bolts 30 (see Fig. 6). Affixed to the shaft 28 intermediate its ends is a sector gear 31 which meshes with the upper toothed sector of a gear 24. It will be seen, therefore, that movement of rod 16 to the right, as viewed in Fig. 3, causes clockwise rotation of shaft 28.

Affixed to the left-hand end of shaft 28, as viewed in Fig. 4, to rotate therewith is an upwardly locking segment 32. The upper arcuate end of segment 32 is provided with a notch 32a (see Fig. 5) adapted for cooperation with a locking dog 33. The notch 32a is elongated to permit the segment to rock through a limited angle when the dog 33 is in a locking position within the notch. Attached to the top edge of segment 32 is a dog depressor bar 32b (see Fig. 5). Bar 32b overlies the notch 32a for a part of its length. A portion 32c of the bar is offset upwardly from and is concentric with the top edge of the segment 32.

As best seen in Fig. 4, locking dog 33 is substantially U-shaped. The lower leg 33a of the dog 33 extends into the notch 32a (see Fig. 5) and the upper or body portion 33b is disposed with clearance between confronting parallel surfaces 4c and 4d formed integrally with the upper casing end wall 4a. Dog 33 is pivotally suspended from the free end of one arm 34a of a bell crank lever 34, the other arm 34b of which has attached thereto, such as by tap screws 35, an armature 36. Lever 34 is bifurcated to straddle bracket 8, and is pivotally supported by trunnions 8a in the aforementioned bracket 8 through the medium of trunnion screws 37 threaded in the lever 34 and secured by nuts 38 (see Fig. 3). Bracket 8 is longitudinally disposed beneath the arm 34a of lever 34 and extends with clearance through the lever opposite trunnions 8a. As previously noted, the bracket 8 is mounted at its ends on end walls 4a and 4b. It will be seen from Fig. 4 that the arm 34a of lever 34 is substantially horizontal while the arm 34b is substantially vertical. This causes the lever 34 to be biased in the counterclockwise direction, as viewed in Fig. 4, by the unbalanced weight of the arm 34a. It will also be seen from Fig. 5 that movement of dog 33, and hence rotation of lever 34 is permitted only when the dog 33 is between the notch 32a and the offset portion 32c of the depressor bar 32b.

An electromagnet 41 is attached by threaded core bolts 39 and nuts 40 to a transverse depending portion 8b of the bracket 8. The other ends of core bolts 39 carry pole pieces 39a which attract the armature 36 when the electromagnet

is energized. Attraction of the armature 36 by the electromagnet causes the lever 34 to be urged in a clockwise direction in opposition to its bias. Conversely, deenergization of the electromagnet releases the armature 36 so that lever 34 may rotate counterclockwise due to its bias.

The parts are so proportioned that lever latch 12 is in the padlocked latching position shown in Fig. 3 when locking segment 32 is positioned 10 as shown in Fig. 5. Electromagnet 41 is then deenergized and dog 33 is biased downwardly into notch 32a. If a switchman then desires to release the lock, he first removes the padlock, and then depresses foot pedal 15. This rotates the 15 segment 32 clockwise until the left-hand edge of the notch 32a, as viewed in Fig. 5, is brought into contact with the dog 33. In this position of segment 32, the lever latch 12 still does not permit the hand-throw lever 2 to be swung out of jaw 3. This condition exists when the padlock control of the lock is removed, but the distant electrical control has not been actuated to permit an unlocking of the switch operating mechanism. If, however, the condition of the distant electrical control is such that electromagnet 41 is energized, then dog 33 is moved upwardly out of notch 32a. Accordingly, the segment 32 then may be rotated clockwise by further depression of pedal 15 to an extreme unlocking position in which the dog 33 is positioned along the top edge of the segment just clear of the left-hand limits of the offset portion of bar 32b. The lever latch 12 is then clear of jaw 3. Under these conditions the padlock has been removed and the distant electrical control has been actuated to permit an unlocking of the switch operating mechanism. By reason of the movement of the lock rod 23 into the path of pedal 15, segment 32 remains in its unlocking position so long as the hand-throw 40 lever 2 is out of the jaw 3, and, during such time, the external control circuit may or may not be actuated to energize the electromagnet. When the lever 2 is returned to its normal position in jaw 3, the lever latch 12 is rotated under the 45 action of the spring bias to its extreme latching position. Segment 32 is then rotated counterclockwise, as viewed in Fig. 5, to an extreme locking position. During this movement of segment 32, depressor bar 32b forces dog 33 downwardly 50 into notch 32a. When the movement is completed, dog 33 just abuts the right-hand edge, as viewed in Fig. 5, of notch 32a. The dog returns to the position in the notch shown in Fig. 5 when foot pedal 15 is depressed slightly to insert 55 the padlock bail 13.

If an attempt is made to operate the lock with electromagnet 41 deenergized, any force acting through segment 32 which tends to misalign or otherwise damage dog 33 and lever 34 is opposed 60 by a reactive force upon engagement of the dog with the surface 4c.

An important feature of my invention is embodied in the mechanism which forces dog 33 to its locking position in notch 32a when segment 65 32 is rotated counterclockwise by the spring bias. This mechanism includes the sloping right-hand end, as viewed in Fig. 5, of the offset portion 32c of depressor bar 32b. It is obvious that this feature is desirable in order to insure a positive break 70 in the magnetic attraction of the armature 36 or to overcome a sticking of the movable parts.

A drum-type circuit controller 42 (see Fig. 4) is mounted on a portion of shaft 28 for rotation therewith. Another drum-type circuit controller 75 43 is rotatably mounted on another portion of

shaft 28. Both controllers are provided with a plurality of contact bands 44 which cooperate with pairs of contact fingers 44a and 44b disposed on opposite sides of shaft 28 (see Fig. 3) and carrying circuit controlling contacts 44c. The contact bands 44 are secured at their ends within longitudinal slots provided in the insulating drums of the controllers. By assembling the bands in the proper positions on the drums and by varying their lengths, the contacts 44a and 44b can be made to make or break a contact in any desired position of foot pedal 15. The contact fingers 44a and 44b are secured by means of terminal posts 45 to an insulating terminal board 46, which, in turn, is secured by tap screws 47 to a boss formed integrally in upper casing 4. The upper ends of each pair of contact fingers 44a and 44b extend above the associated drum controller and are provided with clearance holes through which the threaded stud extensions of an insulating bridging member 48 project. Nuts 49 screw onto the projecting ends of the stud extensions and may be tightened against the outer surfaces of the fingers to effect an urging of the finger ends together which, in turn, produces an increase in contact pressure between the fingers and contact bands 44. Thus an adjustment of the contact pressure to any degree desired is obtained merely by tightening or loosening the nuts 49.

As best seen in Figs. 6, 7 and 8, the drum controller 43 is fixed on a spool 50 which is rotatable on the shaft 28 and is driven by a lost-motion connection with the shaft and a toggle mechanism. One end of the spool 50 is provided with an integral arcuate projection 50a partially encircling the shaft 28. A collar 51 secured to the shaft 28 for rotation therewith forms the journal for the shaft 28 in the bearing 29a, and is provided at one end with an integral arcuate projection 51a which engages the projection 50a. The projections 50a and 51a together do not completely encircle shaft 28. These projections cooperate to at times drivingly connect shaft 28 and spool 50, and together form the lost-motion connection previously referred to. The toggle mechanism includes a depending portion 50b of spool 50, a pivot pin 52 extending through the portion 50b, a compression spring 53, a guide pin 54, and a knife-edge 55 which rides in a bearing 29c formed in a depending portion of bracket 29. Guide pin 54 is pivoted on pin 52 and extends through spring 53 and knife-edge 55 (see Fig. 6).

As illustrated in Figs. 6 and 7, the shaft 28 has rotated the controller 43 counterclockwise, through engagement of the left ends of projections 51a and 50a, as viewed in Fig. 8, to the position in which the depending portion 50b of the spool 50 is vertical. Further counterclockwise rotation of the shaft 28 will cause the toggle mechanism to go over center with a snap action and thereby rapidly throw the depending portion 50b to the right under the force of the expanding spring 53. This throw to the right produces a quick-acting counterclockwise rotation of the drum controller 43 which is in the same direction as, but which, due to its rapidity, is relative to the rotation of the shaft 28. In like manner, clockwise rotation of shaft 28 rotates spool 50 clockwise through engagement of the right ends of projections 51a and 50a, as viewed in Fig. 3, until the depending portion 50b is vertical, from which point a slight additional clockwise rotation of the shaft will cause a quick-acting clockwise rotation of the drum controller relative

to the shaft. Rotation of the controller 43 in either direction is limited by engagement of one or the other of two stop lugs 50c integrally formed on opposite sides of the spool 50 with one of two stops 29b integrally formed on the bracket 29. It will thus be seen that by properly arranging the contact bands 44 a positive and quick-acting completion and interruption of the circuits associated with controller 43 will be had during an operation of the lock.

As best seen in Fig. 4 the end wall 4b is provided with a recess 4e in its upper portion. Secured by tap screws 56 in an aperture in the recess 4a is a spring-loaded push button 57 for effecting an emergency unlock of the electrically controlled locking mechanism. Push button 57 is positioned in recess 4e directly opposite the armature 36 so that when the button is pressed inwardly an insulating plunger 57a is moved endwise to engage the depending leg of lever 34 and force the attached armature against the pole pieces 33a. This causes the lever 34 to rock on trunnions 3a and urge the dog 33 out of notch 32a to effect an unlock of the normally electrical- 20 controlled locking mechanism. A feature of this emergency unlock means resides in the provision of spring metal contact fingers 58 and 59 which are adapted to engage contact points on opposite sides of plunger 57a when the push button is in its normal unoperated position, but which fingers are out of engagement with the contact points when the plunger is moved endwise during an emergency unlock operation. The fingers 58 and 59 are attached to terminal posts 60 mounted on an insulating back plate of the push button, and the contact points are electrically connected through the plunger 57a to form a contact 58—59. The contact 58—59 may be used as a circuit controlling contact in any suitable external circuit wherein an indication of the emergency unlock is desired. Access to push button 57 is afforded through a hand hole 7c in cover 7 which hand hole 7c is provided with a hinged water-tight cover 61 adapted to be padlocked by means of a standard hasp and eye 61a.

Mounted in another aperture in the recess 4e is an indication light 62, the lamp 62a of which is on the outer side of the recess so that when the light is energized, it is externally visible through a sight and vent tube 63 mounted in cover 61. The light 62 is provided for direct connection in the external control circuit to the electromagnet 41 by means of terminal wires 62b. It is therefore apparent that energization or deenergization of the external control circuit to the electromagnet will at all times be indicated by the presence or absence, respectively, of the flow from lamp 62. Accordingly, the indication light feature enables a switchman to ascertain exactly when permission to operate the lock has been obtained from the distant electrical control and obviates the requirement inherent in older forms of electric switch locks of removing the padlock and making possible several repeated attempts to operate the lock.

A night service light 64 (see Fig. 2), the energization of which may be supplied from an external power source, is suitably attached, such as by bolts 65, to the inner side of the recess 4e for facilitating the making of minor repairs and adjustments to the lock during periods of darkness. Provisions may be made for energizing the light 64 only during periods of usage or for continuously energizing the light during cold

weather to prevent formation of ice on the contacts.

A vent tube 66 (see Fig. 4) similar to sight and vent tube 63 is provided in the end of upper casting 4 opposite to that in which tube 63 is mounted to insure cross circulation of air over all heat-producing contacts and electromagnet surfaces. The lock is also provided with a standard type of support bracket 67 (see Fig. 4). The bracket 67 is adapted to guide and support a well-known form of lock bar for insuring against movement of the switch points when the hand-throw lever 2 occupies its normal position. The usual form of lock bar is connected at its one end to the movable switch rails and provided at its other end with a recess for receiving the lever 2.

If it becomes necessary to repair any part of the electrical locking mechanism, the electrical operating unit comprising the casing 4 and the parts within it may be readily separated from the base unit which includes the casing 5. This separation is accomplished simply by removing the four through bolts 6. The lower teeth of gear 24 readily separate from the rack on rod 16b to permit separation of the two units. These gear teeth also readily engage each other when the operating unit is to be replaced. While the operating unit is removed, the latch 12 and padlock 13 are still effective to retain the switch operating lever 2 in its normal position.

Although I have herein shown and described only one form of an electric lock embodying my invention, it is understood that various changes and modifications may be made therein within the scope of the appended claims without departing from the spirit and scope of my invention.

Having thus described my invention, what I claim is:

1. An electric lock for railway track switches comprising a latch movable between a range of latching and unlatching positions, biasing means for moving said latch to its extreme latching position, a movable member for moving said latch to its unlatching position against said biasing means, a locking member movable with said movable member through a range of locking and unlocking positions, a locking dog cooperating with said locking member to prevent movement of said locking member and said movable member when said members are in their respective locking and latching positions, electromagnetic means including an armature connected to said locking dog and effective when energized to move said dog out of locking engagement with said locking member to permit movement of said movable member and said locking member, an electrical circuit controller including a set of contacts; a lost motion connection between said locking member and said contacts, a toggle connection between said locking member and said contacts, said connections permitting operation of the movable member a predetermined degree before operation of said set of contacts; and means for locking said movable member in an intermediate position against the bias of said biasing means, the controller contacts being inoperative when said movable member is in its intermediate locked position.

2. An electric lock for railway track switches comprising a latch movable between a range of latching and unlatching positions, biasing means for moving said latch to its extreme latching position, a movable member for moving said latch to its unlatching position against said biasing means, a locking member movable with said mov-

able member through a range of locking and unlocking positions, a locking dog cooperating with said locking member movable between a first position for locking said locking member and a second position for unlocking said locking member, means on said locking member for biasing said locking dog to its first position to restrict movement of said member to its locking positions, electromagnetic means including an armature connected to said locking dog and effective when energized to move said locking dog to its second position to permit movement of said movable member and said locking member, an electrical circuit controller including a set of contacts; a lost motion connection between said locking member and said contacts, a toggle connection between said locking member and said contacts, said connections permitting operation of the movable member a predetermined degree before operation of said set of contacts; and means for locking said movable member in an intermediate position against the bias of said biasing means, the controller contacts being inoperative when said movable member is in its intermediate locked position.

3. A circuit controller comprising a rotatable shaft, two contact drums, one of said contact drums being fixed on said shaft, a spool rotatable on said shaft and carrying the second drum, an arcuate projection on one end of said spool, a collar fixed on the shaft adjacent said one end of the spool, an arcuate projection on the collar extending toward the spool so as to engage the projection thereon when said shaft is rotated, said two projections occupying less than the entire shaft periphery so as to form a lost motion connection between said spool and said shaft, a toggle mechanism connecting the spool to a fixed connection so that when the shaft is rotated beyond a predetermined point in its travel the spool and its contact drum are moved by the toggle mechanism, and stationary contact fingers held in engagement with each of said contact drums.

4. A circuit controller comprising a rotatable shaft, a contact drum rotatably mounted on said shaft, a lost motion connection between said drum and said shaft including a projection on one end of said drum, a member fixed to said shaft adjacent said one end of said drum and a projection on said member extending toward said one end of said drum so as to engage the projection thereon when said shaft is rotated; a toggle mechanism connecting said drum to a fixed connection so that when said shaft is rotated beyond a predetermined point in its travel the contact drum is moved by the toggle mechanism, and stationary contacts held in engagement with said contact drum.

5. A circuit controller comprising a rotatable shaft, a contact drum rotatably mounted on said shaft, a lost motion connection between said contact drum and said shaft for rotating said drum, a toggle mechanism connecting said contact drum to a fixed connection so that when said shaft is rotated beyond the predetermined point in its travel the contact drum is rotated by said toggle mechanism, and stationary contacts held in engagement with said contact drum.

6. A circuit controller comprising a rotatable shaft, two contact drums, one of said contact drums being fixed on the shaft, a spool rotatable on said shaft and carrying the second drum, an arcuate projection on one end of said spool, a collar fixed on the shaft adjacent said one end of the spool, an arcuate projection on the collar

11

extending toward the spool to engage the projection thereon when said shaft is rotated, both said projections occupying less than the entire shaft periphery to form a lost motion connection between said spool and said shaft; a toggle mechanism including an extending portion on said spool, a stationary bearing, a knife edge riding on said bearing, a guide pin pivoted at one end to said extending spool portion and passing through said knife edge and bearing, and a spring interposed between said knife edge and said extending spool portions whereby the spool and its contact drum is rotated when the shaft is rotated beyond a predetermined point in its travel; and stationary contact fingers held in engagement with each of said contact drums.

7. A circuit controller comprising a rotatable shaft, a contact drum rotatably mounted on said shaft, a lost motion connection between said drum and said shaft including a projection on one end of said drum, a member fixed to said shaft adjacent said one end of said drum and a projection on said member extending toward said one end of said drum so as to engage the projection thereon when said shaft is rotated; a 25 toggle mechanism including an extending portion on said drum, a stationary bearing, a knife edge riding on said bearing, a guide pin passing through said knife edge and said bearing, and a spring interposed between said knife edge and said extending portion whereby said contact drum is moved when the shaft is rotated beyond a predetermined point in its travel; and

stationary contacts held in engagement with said contact drum.

8. A circuit controller comprising a rotatable shaft, a contact drum rotatably mounted on said shaft, a lost motion connection between said contact drum and said shaft for rotating said drum, a toggle mechanism including an extending portion on said drum, a stationary bearing, a knife edge riding on said bearing, a guide pin passing through said knife edge and said bearing, and a spring interposed between said knife edge and said extending portion whereby said contact drum is moved when the shaft is rotated beyond a predetermined point in its travel; and stationary contacts held in engagement with said contact drum.
